Primary Examiner — Ricky Pham**CLAIM**

The ornamental design for an electric hot pot, as shown and described.

DESCRIPTION

FIG. 1 is a rear and top perspective view of an electric hot pot, showing my new design;

FIG. 2 is a front and bottom perspective view thereof;

FIG. 3 is a top plan view thereof;

FIG. 4 is a bottom plan view thereof;

FIG. 5 is a left side elevation view thereof;

FIG. 6 is a right side elevation view thereof;

FIG. 7 is a rear elevation view thereof; and,

FIG. 8 is a front elevation view thereof.

The broken lines in the figures illustrate portions of the electric hot pot that form no part of the claimed design.
